UNITED STATES PATENT OFFICE

144,541

DESIGN FOR A COMBINED CHIP HOLDER AND ASH TRAY

Harry L. Canova, North Hollywood, Calif.

Application November 19, 1945, Serial No. 123,906

Term of patent 14 years

(Cl. D85—2)

To all whom it may concern:

Be it known that I, Harry L. Canova, a citizen of the United States, residing in North Hollywood, in the county of Los Angeles and State of California, have invented a new, original, and ornamental Design for a Combined Chip Holder and Ash Tray, of which the following is a specification, reference being had to the accompanying drawing, forming part thereof.

Fig. 1 is a perspective view of a combined chip holder and ash tray, showing my new design. Fig. 2 is a top plan view thereof.

I claim:

The ornamental design for a combined chip holder and ash tray, substantially as shown.

HARRY L. CANOVA.
